5 Claims. (Cl. 197—42)

This invention relates to a type bar rest support for typewriters and like machines having a substantially semicircular segment with a plurality of type bars pivotally mounted thereon at differential angular positions, said support comprising an arcuate element for cushioning the head of said type bars when restored, said element being mounted for radial as well as tangential displacement on an arcuate guide secured to said segment.

Many rest supports of the above kind have been proposed to reduce the noise and to prevent the rebound and the vibrations caused by the shock of the type bars when restored against the arcuate element.

In a known rest support, the arcuate element is mounted on the type bar segment by yieldable means formed of a pair of leaf springs, each spring having one end secured to a projection of the element and the other end pivoted on the segment, compensating weights being secured to the two ends of the element. Since the leaf springs directly connect the element with the segment, they are differently affected by the different type bars when restored, whereby some type bars will rebound or vibrate more than others.

In another known rest support, the arcuate element is mounted for radial as well as tangential movement on an arcuate guide secured to the segment. In this support the arcuate element is connected to the guide by yieldable means formed of a spiral spring tensioned between the two ends of the guide and embraced by a flexible tube supporting said element. A disadvantage of this rest support is due to the friction of the spring into the tube. Furthermore, the lateral type bars tension the spring substantially less than the central type bars, whereby some type bars will rebound more than others as in the above case.

The main object of the invention is to provide a type bar rest support simple and inexpensive to manufacture and obviating all the above disadvantages.

Another object is to provide a type bar rest support adapted to be affected substantially in a constant manner irrespective of the angular position of the cushioned type bar.

With these and other objects in view, in a typewriter having a substantially semicircular segment with a plurality of type bars pivotally mounted thereon at differential angular positions, I now provide the combination of an arcuate element for cushioning the head of said type bars when restored, an arcuate guide secured to said segment and mounting said element for radial as well as tangential relative displacement, yieldable means for connecting each one of the two ends of said element to said guide, and intermediate means interposed between each one of said two ends and said yieldable means and so pivoted as to enable said yieldable means to be affected by said element under the shock of the restored type bar substantially in a constant manner irrespective of the angular position thereof.

Other objects, features and advantages of the invention

2

will become apparent from the following detailed description of a preferred embodiment thereof, made with reference to the accompanying drawing, wherein:

FIG. 1 is a right hand longitudinal sectional view of a typewriter segment embodying a type bar rest support according to the invention;

FIG. 2 is a partial sectional front view of the rest support of FIG. 1;

FIG. 3 is a sectional view taken on the line III—III of FIG. 2.

With reference to FIGS. 1 and 2, the numeral 6 indicates a substantially semicircular segment of a conventional typewriter. A plurality of type bars 4 is pivotally mounted on a pivot wire 5 of the segment 6 at differential angular positions. The type bars 4 normally contact a type bar rest support generically indicated by the numeral 7.

The support 7 comprises an arcuate element or pad 8 (FIG. 2) for cushioning the head of the type bars 4 when restored. The pad 8 is made of a suitable moulded resilient material, such as rubber or plastic, and is mounted for radial as well as tangential displacement on an arcuate guide 9, 9 (FIG. 1). The guide 9, 9 is formed of a pair of symmetric plates 9 mutually contacting along a rim 9' and fastened by means of studs 10 (FIG. 2). The plates 9 in turn are secured to the segment 6 (FIG. 1) by means of two rods 11. The pad 8 is located between the plates 9 and is provided with a pair of arcuate notches 12 each one housing a second rim 13 of the corresponding plate 9.

Each one of the two ends of the pad 8 (FIG. 2) is connected to the guide 9, 9 by yieldable means 14, intermediate means 15, 16 being interposed between each end of the pad 8 and the yieldable means 14. More particularly, said yieldable means 14 are formed of a pair of spiral springs 14 tangentially located within the guide 9, 9 in a portion deprived of the rims 9' and each one connected at one end, namely at the lower end, to a pin 21 secured on the two plates 9 (FIG. 3). The intermediate means 15, 16 are formed of a pair of two armed levers 15 (FIG. 2) associated with said pair of springs 14 and radially located at the corresponding end of the guide 9, 9. Each lever 15 is pivoted on a pin 22 of a corresponding link 16, which in turn is pivotally linked on a pin 23 secured to the corresponding end of the two plates 9 and is tangentially located within the guide 9, 9. A first arm 20 of each lever 15 is connected to the other end, namely to the upper end, of the corresponding spring 14, while another arm 19 of each lever 15 is connected to a ring 18 (FIG. 3) protruding out of the corresponding end of the pad 8. The two rings 18 (FIG. 2) are each one secured to a corresponding end of an inextensible reinforcing cable 17 made of flexible vegetable or synthetic fiber moulded within the resilient material of the pad 8 (see also FIG. 1).

55 The type bar rest support 7 operates as follows.

When a central type bar 4 (FIG. 2) is restored, its shock against the inner edge of the pad 8 causes this pad to be altered in form and substantially displaced radially downwards. This displacement through the rings 18 is 60 tangentially transmitted to the levers 15 which are rocked in a manner as to tension the springs 14. The power of the shock is thus rapidly absorbed by the springs 14 which cushion the type bar 4 and prevent same from rebounding or vibrating. Obviously the alteration in form and the 65 displacement of the pad 8 is followed by the other ad-

jacent type bars, whose restoring springs, not shown in the drawing, contribute in absorbing the power of shock. In this case the links 16 are not affected by the rocked levers 15, because the force applied by each spring 14 to the corresponding lever 15 and the force applied thereto by the ring 18 are tangential to the guide 9, 9 and substantially parallel to the direction determined by the pins 22 and 23.

On the contrary, when a lateral type bar 4 is restored, its shock against the pad 8 causes alteration in form and substantially radial displacement of the pad 8 at the corresponding end. The tangential component of the force applied by the corresponding ring 18 to the lever 15 and caused by this radial displacement is less than in the above case, whereby the levers 15 remain substantially unrocked. The displacement of the pad 8 causes rather a radial component of the force applied by the ring 18 to the lever 15 which now through the pin 22 urges the corresponding link 16 to rock about its pin 23 and against the action of the same spring 14. Therefore in this case, too, the spring 14 corresponding to the shocked end of the pad, and in a minor amount the other spring 14, are tensioned substantially in a manner similar to that of the case of the central type bars.

It is thus clear that the intermediate means 15, 16 interposed between each end of the element 8 and the yieldable means 14 are so pivoted as to enable said yieldable means to be affected by said element under the shock of the restored type bar substantially in a constant manner irrespective of the angular position thereof.

It will be understood that many changes, improvements and addition of parts may be made in the above embodiment without departing from the scope of the invention. It is, therefore, intended that all matter contained in the above description or shown in the accompanying drawing shall be interpreted as illustrative and not in a limiting sense.

What I claim is:

1. In a typewriter having a substantially semicircular segment with a plurality of type bars pivotally mounted thereon at differential angular positions, a type bar rest support comprising in combination:

- (a) an arcuate element for cushioning the head of said type bars when restored,
- (b) an arcuate rigid guide secured to said segment and mounting said element for radial as well as tangential relative displacement,
- (c) a pair of springs for connecting each one of the two ends of said elements to said guide,
- (d) and intermediate means interposed between each one of said two ends and the corresponding spring of said pair so pivoted on said guide as to enable said pair of springs to be affected by said element under the shock of the restored type bar substantially in a constant manner irrespective of the angular position thereof.

2. In a typewriter having a substantially semi-circular segment with a plurality of type bars pivotally mounted thereon at differential angular positions, a type bar rest support comprising in combination:

- (a) an arcuate element for cushioning the head of said type bars when restored,
- (b) an arcuate guide secured to said segment and mounting said element for radial as well as tangential relative displacement,
- (c) a pair of yieldable means each one connecting a corresponding end of said element to said guide,
- (d) and a pair of two armed levers associated with said pair of yieldable means, a first arm of each lever being connected to the corresponding yieldable means, another arm being connected to the corresponding end of said element, said levers being radially located at the corresponding end of said

guide and being so pivoted as to enable said yieldable means to be affected by said element under the shock of the restored type bar substantially in a constant manner irrespective of the angular position thereof.

3. In a typewriter having a substantially semicircular segment with a plurality of type bars pivotally mounted thereon at differential angular positions, a type bar rest support comprising in combination:

- (a) an arcuate element for cushioning the head of said type bars when restored,
- (b) an arcuate guide secured to said segment and mounting said element for radial as well as tangential relative displacement,
- (c) a pair of springs each one connecting a corresponding end of said element to said guide,
- (d) a pair of two armed levers associated with said pair of springs, a first arm of each lever being connected to the corresponding spring, another arm being connected to the corresponding end of said element,
- (e) and a pair of links each one pivotally linked to a corresponding end of said guide and tangentially located therein, each one of said levers being radially located at a corresponding end of said guide and being so pivoted on the corresponding link of said pair as to enable the corresponding spring to be affected by said element under the shock of the restored type bar substantially in a constant manner irrespective of the angular position thereof.

4. In a typewriter having a substantially semicircular segment with a plurality of type bars pivotally mounted thereon at differential angular positions, a type bar rest support comprising in combination:

- (a) an arcuate element for cushioning the head of said type bars when restored,
- (b) an arcuate guide secured to said segment and mounting said element for radial as well as tangential relative displacement,
- (c) a pair of spiral springs, each one connected at one end to said guide,
- (d) a pair of two armed levers associated with said pair of springs, a first arm of each lever being connected to the other end of the corresponding spring, the other arm being connected to the corresponding end of said element,
- (e) and a pair of links each one pivotally linked to a corresponding end of said guide and tangentially located therein, each one of said levers being radially located at a corresponding end of said guide and being so pivoted on the corresponding link of said pair as to enable the corresponding spring to be affected by said element under the shock of the restored type bar substantially in a constant manner irrespective of the angular position thereof.

5. In a typewriter having a substantially semicircular segment with a plurality of type bars pivotally mounted thereon at differential angular positions, a type bar rest support comprising in combination:

- (a) an arcuate element for cushioning the head of said type bars when restored, said element being made of moulded resilient material,
- (b) an inextensible reinforcing cable moulded within the material of said element,
- (c) a ring secured at each end of said cable and protruding out of the corresponding end of said element,
- (d) an arcuate guide secured to said segment and mounting said element for radial as well as tangential relative displacement,
- (e) a pair of spiral springs each one connected at one end to said guide,
- (f) a pair of two armed levers associated with said pair of springs, a first arm of each lever being connected to the other end of the corresponding spring,

the other arm being connected to the corresponding ring of said cable,

(g) and a pair of links each one pivotally linked to a corresponding end of said guide and tangentially located therein, each one of said levers being radially located at a corresponding end of said guide and being so pivoted on the corresponding link of said pair as to enable the corresponding spring to be affected by said element under the shock of the restored

type bar substantially in a constant manner irrespective of the angular position thereof.
